Geo. P. Kinneal Attorney

UNITED STATES PATENT OFFICE.

WALTER BETHKE, OF WALBURG, TEXAS.

INSTRUMENT BOARD AND ENGINE BRACE.

Application filed March 18, 1921. Serial No. 453,514.

To all whom it may concern:

Be it known that I, WALTER BETHKE, a citizen of the United States, residing at Walburg, in the county of Williamson and State 5 of Texas, have invented certain new and useful Improvements in an Instrument Board and Engine Brace, of which the following is a specification.

This invention relates to attachment for 10 a motor driven vehicle, and has for one of its objects to provide a simply constructed combined bracing and holding device adapted for coupling the cylinder head of the engine of the motor vehicle to the instrument board and mutually bracing, supporting and reinforcing the instrument board and preventing displacement under the severe strains to which the instrument board 15 is subjected.

With these and other objects in view, the invention consists in certain novel features of construction as hereinafter shown and described and then specifically pointed out in the claim, and in the drawing illustrative 20 of this preferred embodiment of the invention.

Figure 1 is a side elevation of a portion of the engine cylinder head, a portion of the instrument board, and the hood, the hood and instrument board being in section.

Fig. 2 is an enlarged detached plan view of the improved attachment.

Fig. 3 is an end elevation of the device as shown in Fig. 2.

The improved device is shown applied to a conventional cylinder head 10 and instrument board 11 of a motor driven vehicle, a section of the hood being represented at 12.

The bolts by which the cylinder head is 40 retained in position are indicated at 13, the clamp nuts at 14.

The improved attachment includes a clamp member 15 having apertures 16 at the ends adapted to engage over a pair of the bolts 13 and be held in position by the nuts 14 as shown.

By this means the same bolts and nuts which held the cylinder head in place are utilized to hold the clamp member.

Extending from the clamp member at one 50 end is a brace member 17, and obliquely to the longitudinal axis of the clamp member and upturned at the outer end as shown at 18 and perforated to receive fastening device 19 whereby the member is attached to 55 the instrument board 11.

Extending from the clamp member at the other end is a brace member 20 with its other end upturned as at 21 and perforated to receive a fastening device 22, whereby 60 the member 20 is attached to the instrument board.

By this simple means the instrument board is firmly braced and supported from the engine and firmly resisting displacement 65 under the severe strain to which it will be subjected in use especially when running over rough roads.

The improved device is simple in construction, can be constructed from a single piece 70 of rod of metal preferably steel, as light as possible consistent with the strains to which it will be subjected.

The preferred embodiment of the invention is disclosed in the drawings and set forth 75 in the specifications, but it will be understood that any modifications within the scope of the claim may be made in the construction without departing from the principle of the invention or sacrificing any of its advantages.

Having thus described the invention what is claimed as new is:—

The combination with the instrument board and the motor casing of a motor 85 driven vehicle, including the clamp bolts of the engine casing head, of a stay member perforated to engage a plurality of said bolts and held in place by the nuts of the same, a brace member extending obliquely 90 from one end of the stay member and attached at its free end to the instrument board, and a brace member extending obliquely from the other end of the stay member and attached to the instrument board. 95

In testimony whereof, I affix my signature hereto.

WALTER BETHKE,
